CLAIM

The ornamental design for a cartridge for game machine, as shown and described.

DESCRIPTION

FIG. 1 is a top, front and right side perspective view of a cartridge for game machine showing my new design; FIG. 2 is a bottom, rear and right side perspective view thereof;

FIG. 3 is a rear elevational view thereof;

FIG. 4 is a top plan view thereof;

FIG. 5 is a front elevational view thereof;

FIG. 6 is a right side elevational view thereof, the left side being a mirror image;

FIG. 7 is a bottom plan view thereof;

FIG. 8 is a sectional view thereof, taken along line 8—8 of FIG. 4.

FIG. 1

FIG. 2

FIG. 3

FIG. 4

FIG. 6

FIG. 5

FIG. 7

FIG. 8
